UNITED STATES PATENT OFFICE.

ALBERT A. BEALS, OF CLARENCE, MISSOURI.

CHAIN-REEL.

1,112,968.

Specification of Letters Patent.

Patented Oct. 6, 1914.

Application filed September 18, 1913. Serial No. 790,433.

To all whom it may concern:

Be it known that I, ALBERT A. BEALS, a citizen of the United States, and a resident of Clarence, in the county of Shelby and State of Missouri, have invented a new and useful Improvement in Chain-Reels, of which the following is a specification.

My present invention relates to grain reels, and more particularly to a reel to be used on all types of grain harvesters such as self-binders, headers and combined machines, my object being to provide a reel which may be mounted low down on the machine frame and which will not interfere in any way with the vision of the operator from his seat.

A further object of my invention is to provide a reel which will be capable of a greater variety and range of adjustments than usual, 20 may be effected in order to meet the requirements of grain of different heights and permit of uniformly good results.

A further object of my invention is to provide a reel in which the grain slats are flexibly supported at least to a degree sufficient to permit of enough movement or play so that they will not necessarily break when they encounter an obstruction, as is at present the case.

30 A still further object of my invention is to provide a reel in which the slats, moving with the grain, travel in a straight line, doing away with the at present tendency to lift the grain as it is deposited on the platform, and promoting a uniformly better operation and result.

Still further objects and their resulting advantages will be better understood from the following description in which reference 40 is made to the accompanying drawings, forming a part of this specification, and in which,

Figure 1 is a front elevation, Fig. 2 is a detail vertical section through one of the reel supporting standards, Fig. 3 is a vertical section taken substantially on line 3-3 of Fig. 1, Fig. 4 is a horizontal section taken axially along the inner portion of the reel shaft, Fig. 5 is a detail view, partly 50 broken away and in section, of the bracket for the inner reel standard, and, Fig. 6 is a detail perspective view showing my improved reel complete with the exception of the adjusting levers.

55 Referring now to these figures, A indicates the frame of a conventional type of

harvesting machine, B indicating the operator's seat, and C indicating the grain platform.

Secured to portions of the frame A at the inner and outer sides of the platform C respectively, are brackets D and D' to which are pivoted the lower ends of the inner and outer reel supporting standards E and E', these pivots being indicated at e. As most clearly shown in Figs. 2, 5, and 6, the standards E and E' are tubular.

Slidably mounted on the standards E and E' are a pair of journal boxes F' of the reel shaft F, the upper portions of the standards having openings e' and pulleys e². Flexible connections G and G' are connected at their outer ends to the journal boxes F' and extended into the openings e' and downwardly over the pulleys e², the connection G of standard E being extended downwardly and rearwardly beneath a pulley d of bracket D and connection G' being extended downwardly and laterally beneath a pulley d' of bracket D' and passing across the front of the machine substantially above the cutter bar C', as shown in Fig. 3, and rearwardly around a pulley d² of bracket D. The rear ends of these flexible connections G and G' are connected to the lower end of an upright lever H intermediately pivoted on the frame at h adjacent the operator's seat B and having a latch mechanism in engagement with a quadrant h' to hold the same and the journal boxes F' in adjusted position.

Secured upon the reel shaft F are a pair of sprocket wheels I and I' spaced apart a distance equal to the width of the reel and located between the supporting standards E and E', alongside which sprocket wheels are arranged the side cross heads J and J' of the reel, extending forwardly and rearwardly, and centrally through which the reel shaft F loosely extends. These cross heads respectively carry at their outer ends rotatable sprocket wheels j and j' in line with the sprocket wheels I and I' to receive the front and rear portions of the endless chains K and K' to which the cross slats L are connected.

The cross heads J and J' are rigidly connected by means of angular arms m at the ends of a sleeve M upon the intermediate portion of the reel shaft F. Upon the inner end portion of the reel shaft is also arranged a sleeve N, connected to the cross head J

by means of angular arms n at one end, and having an upright arm n' to the upper end of which is pivotally connected the forward end of a rearwardly extending connecting rod n' having its rear end similarly connected intermediate the ends of an upright adjusting lever O fulcrumed at its lower end on the frame A adjacent the operator's seat B and having a latch mechanism in engagement with a quadrant o to maintain it in adjusted position. By means of lever O , the reel may be tilted forward or backward at a desired angle.

To collars p' loosely surrounding the sleeve N is rigidly connected the forward end of a rearwardly projecting rod P , the rear end of which is pivotally connected to another lever P' fulcrumed on the frame adjacent the driver's seat B and having a latch mechanism in engagement with a quadrant p . By means of this lever the reel may be moved forwardly and rearwardly, the standards E and E' yielding on their pivots e inasmuch as bearings F' are sufficiently broad to cause the standards to move in unison.

Power is applied, in operation, to the inner end of the reel shaft F through a shaft Q connected thereto by a universal joint q , this shaft being in telescoping sections which, together with the joint q , allows for the several adjustments of the reel before mentioned.

Thus I am enabled to obtain uniformly satisfactory results with grain of different heights and of different kinds, and to do away with many of the difficulties incident to the usual reels, some of which have been before mentioned.

40 I claim:

1. A reel of the character described comprising a pair of cross heads spaced apart and connected, sprocket wheels carried by the ends of said cross heads, endless chains arranged over the said wheels and having cross slats, a shaft extending centrally through the cross heads and provided with sprocket wheels in engagement with the chains, standards pivotally supported at 45 their lower ends, journal boxes for the shaft vertically adjustable on the standards, a lever having connections with said journal boxes for adjusting the same, a lever having connection with the cross heads whereby to tilt the same forwardly and rearwardly on the shaft, and a lever having connections for moving the standards on the pivots whereby to adjust the reel forwardly and rearwardly, for the purpose described.

2. A reel of the character described comprising a pair of spaced chains having cross slats, crossheads having sprocket wheels on which the chains are arranged, a shaft having sprocket wheels for driving the chains and upon which the cross heads are tiltable forwardly and rearwardly, and uprights pivotally mounted at their lower ends and forwardly and rearwardly movable on their pivots and upon which the said shaft is vertically adjustably mounted whereby the said shaft may be adjusted vertically and horizontally.

3. A reel of the character described comprising a pair of spaced chains having cross slats, cross heads having sprocket wheels on which the chains are supported to travel, a driver shaft having sprocket wheels in engagement with the chains and on which the cross heads are mounted, and supporting standards carrying the shaft and pivotally mounted at their lower ends whereby the reel may be adjusted forwardly and rearwardly, substantially as described.

4. A reel of the character described, comprising a pair of cross heads, a pair of spaced chains having cross slats, a shaft having sprocket wheels for driving the chains, bearing members in which the end portions of the said shaft are journaled, a pair of tubular uprights upon which the said bearing members are mounted to move vertically, flexible connections extending upwardly through the tubular uprights and secured to said bearing members, and a lever for actuating the said flexible connections and to permit the raising and lowering of the reel for the purpose described.

5. A reel of the character described, comprising a pair of cross heads, a pair of spaced chains having cross slats, a sleeve 100 extending between and rigidly connecting the said cross heads intermediate their sides, a shaft extending loosely through the said sleeve, sprocket wheels secured on the shaft at the ends of the said sleeve and engaging the spaced chains, a second sleeve disposed upon the shaft adjacent and connected to one of the cross heads and provided with a crank arm, and a lever having connection with the said crank arm whereby to rotate the sleeves and cross heads on the shaft and thus tilt the reel sides in relatively opposite directions.

ALBERT A. BEALS.
